Hanson & Hanson

UNITED STATES PATENT OFFICE.

CHARLES S. BAILEY, OF ASHLAND, PENNSYLVANIA, ASSIGNOR TO SCHUYLKILL ELECTRIC COMPANY, OF PHILADELPHIA, PENNSYLVANIA, A CORPORATION OF PENNSYLVANIA.

ANTITHEFT DEVICE FOR METERS.

Application filed August 3, 1921. Serial No. 489,654.

To all whom it may concern:

Be it known that I, CHARLES S. BAILEY, a citizen of the United States, residing in Ashland, Pennsylvania, have invented Anti-theft Devices for Meters, of which the following is a specification.

One object of this invention is to provide a relatively simple, inexpensive device for so enclosing the terminals of a meter as to prevent access to them by unauthorized persons and to render impossible the placing of jumpers upon the conductors adjacent the meter or such other tampering with the terminals or conductors as might result in theft of current or injury to the meter itself.

It is further desired to provide a device of the character above described which shall be easily applied to or removed from the meter and which after having been placed thereon, may be retained in place by a sealing device.

These objects and other advantageous ends I attain as hereinafter set forth, reference being had to the accompanying drawings, in which,

Fig. 1 is a front elevation of an electric meter, showing my invention as applied thereto;

Fig. 2 is a perspective view of the protective device shown in Fig. 1;

Fig. 3 is a plan of the cut or stamped blank from which my protective device may be formed; and

Fig. 4 is a front elevation of the partially assembled protective device made from the blank shown in Fig. 3.

In the above drawings, 1 represents a well known form of electric meter having at what is usually its lower side a hollow projecting portion 2 in which are located the terminals 3, 4, 5 and 6 of the instrument. From these, conductors 7, 8, 9 and 10 run from the instrument, usually through one or more closed conduits. A pin or post 11 projects from the front face of the part 2 of the meter and through it adjacent its free end there is usually formed a transverse hole or passage for the reception of a wire 12, whose ends are connected by a lead or other suitable seal 13.

For the purpose of enclosing the terminals 3-6 and those portions of the conductors 7-10 immediately adjacent thereto

I provide a casing of sheet material which may be of metal, vulcanized fiber, or other suitable substance having a bottom section 14. To the lower edge of this is attached a back section 15 which may be bent at right angles to it and this has attached to each of its ends holding flaps each consisting of a part 18 to the outer edge of which is attached a flap 19.

To each of the side edges of the bottom 14 is hinged a rectangular side piece 16 and at the top edge of said front is hinged a front piece 17 also of rectangular form. Preferably at the center of the bottom member 14 is mounted a bushing 20 of any suitable material, which may if desired be directly connected to the end of a conduit for the reception of the conductors 7-10. Both of the flaps 19 adjacent their outer ends are provided with a hole 21 and a similar hole 22 is formed in the front member 17.

In assembling or constructing my protective device from the blank shown in Fig. 3, the two side members 16 are bent backwardly into positions at right angles to the plane of the front member 14 and the front member 17 is likewise bent back in a plane at right angles to those of the side members 16, as well as to that of the bottom member 14. The back member 15 is then also bent back at right angles to the plane of the bottom member 14 and the members 18 are then turned up at right angles so as to extend respectively adjacent the outside faces of the side members 16. The flaps are then bent at right angles to said members 18 across the front member 17 and are overlapped so that their two holes 21 are in line with each other and with the hole 22 of the top member.

When the parts are in the partially folded positions shown in Fig. 4 the casing may be applied to the projecting portion 2 of a meter and as the folding is completed the post 11 is caused to extend first through the hole 22 of the top member 17 and thereafter through the holes 21 of the flaps 19. The wire 12 is then run through the transverse hole in the post 11 and the seal 13 is applied so as to inseparably hold the ends of the wire together. The seal thus effectually holds my protective device in such position that it completely encloses the terminals of the meter as well as the conductors immediately adjacent thereto, it being understood

that after the device has been brought to the partially folded condition shown in Fig. 4 said conductors are extended through the bushing 20 and attached to said terminals 5 before the post has been inserted in the holes 22 and 21 and the seal applied.

It is now impossible for anyone to tamper with the terminals or the conductors adjacent thereto without first breaking the seal 10 13 or the wire 12 and opening or removing my protective device, which operation if performed by unauthorized persons, could be easily and quickly detected. The conductors 7—10 may be completely protected 15 if desired by being run into a closed conduit immediately after passing through the bushing 20. It is to be further understood that the dimensions of my device are such that it snugly fits the projecting portion 2 of the meter so that this is effectually protected.

From the above description it will be noted that the members 18—19 extend upwardly adjacent the outer faces of the side members 16 and being overlapped across the bottom member 14, serve to hold the side members in place.

I claim:

1. A meter protective device consisting of a casing formed of a body of sheet material folded to provide bottom, front, back and side members; with flaps extending from the side edges of the back member over the outer faces of the side members and across 35 the front member, the latter and the flaps being perforated for the reception of a device for holding them in folded form.

2. A meter protective device consisting of a casing formed of a body of sheet material folded to provide bottom, front, back and side members; with flaps extending

from the side edges of the back member over the outer faces of the side members and across the front member; with means independently of the casing for holding said 45 flaps to the front member.

3. The combination of an electric meter; a folded sheet metal casing enclosing the terminal-containing portion of said meter, said casing including front, bottom, back 50 and side members; flaps holding the side members in place and overlapped on the front member; with a post projecting from the meter and extending through the front and through the overlapping members of 55 the casing.

4. The combination of a meter having a projecting terminal post; a casing consisting of a body of sheet metal having members folded to enclose said terminal 60 portion of the meter and including retaining elements for holding the members in folded relation; with a post on said terminal portion of the meter extending through the retaining portions of the casing; and a seal 65 for normally preventing disengagement of the retaining parts of the casing from the post.

5. A meter protective casing consisting of a single body of sheet metal including a 70 bottom member having an opening for the passage of conductors; front, back and side members respectively connected to said bottom member; and flaps connected to the side edges of the back member, said flaps each 75 consisting of two portions of which one part retains a side member in place, the other portions of said flaps being overlapped over the front member and there being registering holes in the front member and in the 80 overlapping portions of said flaps.

CHARLES S. BAILEY.
